This is a detailed circuit diagram of a vacuum tube radio receiver, specifically a superheterodyne type. The diagram is organized into several vertical columns representing different stages of the signal processing.

- Antenna Stage:** The top left shows an antenna connection with a ground return. Frequency markers 22042 and 203 are present.
- Local Oscillator (LO) Stage:** Located in the top center, it includes a crystal oscillator (3662) and associated frequency markers 16962 , 92 , 73 , 87 , 93 , 80 , 67 , 54 , 329 , 533 , 534 , 535 , Inventor
Alfred Scheunert
By Charles M. Candy Atty:

UNITED STATES PATENT OFFICE.

ALFRED SCHEUNERT, OF CHARLOTTENBURG, GERMANY, ASSIGNOR TO SIEMENS & HALSKE AKTIENGESELLSCHAFT, OF WEINERWERK, SIEMENSSTADT, NEAR BERLIN, GERMANY.

TELEPHONE SYSTEM.

Application filed June 12, 1924, Serial No. 719,568, and in Germany June 16, 1923. Renewed November 9, 1927.

The invention relates to a circuit arrangement for setting up connections with private branch exchange subscribers in automatic telephone systems. It consists in that after 5 a switch has been set on a contact of a line group leading to a private branch exchange, switching means become operative, which place the positioning members of the switch under the control of switching arrangements 10 belonging to a preceding connecting stage.

The arrangement according to the invention can, for instance, be used with advantage in systems in which connections of different value may be set up, for instance 15 local and toll connections. The switching arrangements which render a switch suitable for effecting special circuit changes that only required for high value connections are, for instance, not associated with the switches 20 over which the subscribers' lines are reached but are associated with other preceding switches, of which only a small quantity are provided. In that case the invention enables the positioning members of a switch to 25 be controlled by devices associated with the switch itself in the case of low value connections, but for high value connections the positioning members are controlled from the point provided with switching means for 30 converting the switch.

The drawings comprising Figs. 1-4, inclusive, show by way of example one method of carrying out the invention.

Fig. 1 shows diagrammatically the arrangement of the switches for setting up local and toll calls in a telephone system.

Fig. 2 shows the calling end of the toll operator's cord FA provided with the calling plug *Fst*, an outgoing line accessible at 40 the jack *Kl* and terminating in the pre-selector *IFVW*, and the first group selector *IGWf*. The detail circuits of the above have been omitted since they do not concern the invention.

In Fig. 3 is shown by means of the usual circuit diagrams the second group selectors *IIIGWfa* and *IIIGWfb*.

In Fig. 4 is shown the final selector *LW*.

Local connections between the subscribers 50 *Tln 1* and *Tln 2* are set up by positioning

the following switches: first preselector *I.VW*, second preselector *II.VW*, first local group selector *LGW_o*, second local group selector *II.GW_o* and final selector *LW*.

The second group selectors *II.GWfa* arranged for setting up toll connections can also be used for setting up local connections. It is, however, preferable to so arrange matters that these second group selectors are only available for setting up local connections when all the local group selectors over which local calls can be set up are engaged. A local connection set up over a second group selector arranged for setting up toll connections extends over the following switches: first preselector *I.VW*, second preselector *II.VW*, first local group selector *LGW_o*, back contact *u1*, second toll group selector *II.GWfa*, final selector *LW* to subscriber *Tln 2*.

If the subscriber *Tln 2* is wanted by the toll exchange, the operator at the toll exchange FA plugs into a free jack *Kl* with her plug *Fst*. The preselector *I.FVW* sets itself in known manner on a free succeeding switch, namely on a first group selector *IGWf* that can only be used for toll connections. This first group selector, by means of number impulses, is set on a particular contact group and then in this group seeks a free second toll group selector, namely the pair of group selectors *II.GWfa* and *II.GWfb*. Both group selectors are simultaneously positioned. A free final selector *LW* is taken into use over the group selector *II.GWfa*. The final selector having been positioned, the switch *II.GWfa* is disconnected and the switch *II.GWfb* is connected up. This is effected by switching over suitable contacts, one of which is shown in Fig. 1 and is designated by *u1*. The final setting up of the toll connection and of the speaking route takes place over the group selector *II.GWfb*.

The different connections that can be set up over the group selectors *II.GWfa* and *II.GWfb* will now be described.

The case will first be considered, in which a local connection is to be set up with the direct line subscriber *Tln 2* and in which

this local connection must extend over a toll group selector II.GW_{fa} owing to all second group selectors II.GW_o arranged only for local calls being engaged.

5 The individual circuit changes will now be explained with reference to Figs. 3 and 4.

When the pair of group selectors II.GW_{fa} and II.GW_{fb} are taken into use by a preceding first group selector, a circuit is closed 10 over the test wiper of this first group selector, this circuit extending from earth over the test relay (not shown) of the first group selector, the test lead 1, the off-normal contact 2 *kfa* and the windings I of the relays

15 B1 and C1 and battery to earth. The relays B1 and C1 operate. The relay C1, by closing its contact 3 *c1*, prepares a holding circuit over both its windings I and II. By the opening of the contact 4 *c1*, the release magnets M1 and M2 are disconnected and in

20 place thereof the circuit of the rotary magnets D1 and D2 is prepared at the contact 5 *c1*. At the contact 6 *c1* the test relay P1 is connected to the test wiper 7 of the group

25 selector II.GW_{fa}. The relay B1, which was energized at the same time as the relay C1, at its contact 8 *b1* connects the impulse receiving relay A1 to the lead 9 and at the contact 10 *b1* connects its second winding II

30 B1 to the lead 11. Furthermore, by closing the contact 12 *b1*, it prepares the circuit of the vertical magnets H1 and H2 of the group selectors II.GW_{fa} and II.GW_{fb}. By the opening of the contact 13 *b1*, a premature

35 connecting up of the rotary magnets D1 and D2 is prevented. When the calling station transmits impulses for positioning the second group selector, battery potential is connected to the lead 11 in known manner at a preceding

40 impulse repeater and thereby the relay B1 is maintained energized for the duration of the train of impulses. Impulses are transmitted over the lead 9. The relay A1 is energized at each impulse and at the contacts 14

45 15 *a1* and 15 *a1* closes the circuits of the vertical magnets H1 and H2: earth, contacts 12 *b1* and 14 *c1*, vertical magnet H2, battery, earth. The off-normal contact 2 *kfa* is opened at the first vertical step and thereby

50 the winding I of the relay B1 is disconnected. Furthermore the off normal contacts 16 *kfa* and 17 *kfb* are closed. At the end of the train of impulses, battery is disconnected from the lead 11, thereby de-energizing the relay B1. This closes its contacts

55 13 *b1*, hence the rotary magnets D1 and D2 of both the group selectors are now energized. The circuit for the rotary magnets extends as follows:—earth, contact 13 *b1*,

60 contact 16 *kfa* and in parallel therewith contact 17 *kfb*, contacts 18 *p1*, 5 *c1*, 19 *a1*, rotary magnet D1, battery earth and parallel thereto contact 20 *a1*, rotary magnet D2, battery, earth. When both rotary magnets

65 have operated, the relay A1 is locally ener-

gized: earth, contacts 21 *d1*, 22 *d2*, relay A1 battery, earth. The relay A1 opens its contacts 19 *a1* and 20 *a1*, so that the rotary magnets D1 and D2 are de-energized. Both the group selectors have been moved on one step 70 and the relay A1, on releasing, again closes its back contacts 19 *a1* and 20 *a1*. Thereupon the rotary magnets D1 and D2 can again energize and close the circuit for the relay A1, which again opens the circuits of D1 and D2. The intermittent opening and closing of the circuits of the driving magnets D1 and D2 causes the two group selectors to be synchronously operated.

When a free final selector LW is found, 80 the following test circuit is established: earth, windings I and II of the test relay P1, contact 6 *c1*, wiper 7, contact 23, lead 24, side switch contact 25, (Fig. 4) position 1, winding I of the relay C2, battery, earth. The relays P1 and C2 operate. The relay

85 P1 at contact 18 *p1* (Fig. 3) opens the circuit of the rotary magnets D1 and D2, marks the selected final selector engaged by short circuiting its high resistance winding I at contact 26 *p1* and at contacts 27 *p1* and 28 *p1* it switches through the speaking leads 9 and 11 over the back contacts 29 *u1* and 30 *u1*, the leads 31 and 32, the wipers 33 and 34, the contacts 35 and 36 to the leads 37 and 38 90 extending to the final selector LW, where the bridging relays A2 and B2 are connected up over the side switch contacts 39 and 40 (Fig. 4) in the positions 1 and 2 of the side switch.

The relay C2, operated at the same time as the relay P1, by closing its contact 41 *c2* prepares a holding circuit, which functions when the side switch leaves its position 1. The relay C2 furthermore opens and closes 100 a number of other contacts, over which however circuit changes only take place at later stages in the setting up of the connection.

When the calling party transmits current 110 impulses for setting the final selector on a particular contact group the control relay B2 is energized by the application of battery potential to the lead 11. The relay B2 opens its contact 42 *b2* and thereby prevents the side switch moving on prematurely into the position 2. Impulses are sent over the leads 9, 31 and 37 and operate the impulse receiving relay A2. This at each impulse closes the circuit of the vertical magnet H3: earth, contact 43 *a2*, side switch contact 44 position 1, vertical magnet H3, battery, earth. At the end of the train of impulses, the disconnection of battery potential from the lead 11 causes the release of the relay B2, which at its contact 42 *b2* closes the circuit of a relay F2: earth, contacts 42 *b2*, 45 *a2*, 46 *k3*, side switch contact 47 position 1, relay F2, resistance 48, battery, earth. The relay F2 at its contact 49 *f2* connects up the side switch magnet St, which at its contact 50 *st* 120

125

130

short circuits the relay F2. Thereby the side switch is moved into the second position, in which the rotary magnet D3 is connected up in place of the vertical magnet H3. During the second train of impulses which serve to set the final selector on a particular line, the relay B2 is again energized and opens the contact 42 b2. The impulses, which are received by the relay A2, operate the rotary magnet D3 in the following circuit: earth, contacts 51 p2, 52 g, 53 a2, side switch contact 55 position 2, rotary magnet D3, battery, earth. At the end of this train of impulses the relay B2 again releases and closes the circuit of the relay F2, which connects up the side switch magnet St: earth, contacts 42 b2, 45 a2, 56 w3 (closed on the first rotary step of the switch), side switch contact 57 position 2, relay F2, resistance 48, battery, earth. The side switch moves into its position 3, in which the relay F2 is energized over the contacts 42 b2 and 45 a2 and the side switch contact 58 position 3 and causes the side switch to move on into the position 4. In position 3 of the side switch a relay U2 is energized over its winding I: earth, side switch contact 59 position 3, winding I of the relay U2, resistance 48, battery, earth. The relay U2 is provided with a slow releasing armature, so that the contact 60 u2 remains open a little while after the circuit of the relay U2 has been opened.

In position 4 the free or engaged condition of the wanted line is tested. It will first be assumed that the wanted line is idle. In that case the following test circuit is established: earth, contact 61 g, side switch contact 62 position 4, windings I and II of the relay P2, wiper 63, contact 64, relay 65 associated with the wanted line, battery, earth. The relay P2 operates and marks the selected line engaged by short circuiting its high resistance winding I at contact 66 p2. Furthermore at contact 67 p2 it opens the circuit of the release magnet M3 and at contact 51 p2 it opens the circuit of the rotary magnet D3. This switching operation is required for a connection described later on.

When the relay U2 has released, the relay F2 is energized in the following circuit: earth, contacts 68 a2, 60 u2, side switch contact 69 position 4, relay F2, resistance 48, battery, earth. The relay F2 in the manner already described causes the side switch to move on into the position 5. Since the selected line is free and the relay P2 has therefore been energized, the relay F2 is energized as follows in the position 5 of the side switch: earth, contact 70 p2, side switch contact 71 position 5, relay F2, resistance 48, battery, earth. The side switch therefore moves to position 6. In this position the first call is transmitted to the selected line:

earth, source of ringing current 72a, side switch contact 73 position 6, wiper 74, contact 75, lead 76 of the subscriber's line, subscriber's instrument Tln 2, lead 77 of the subscriber's line contact 78 wiper 79, side 70 switch contact 80 position 6, earth. In the position 6 of the side switch the relay F2 controlling the side switch magnet St is connected over the side switch contact 81 position 6 to a slow interrupter 82. The side switch is moved on into the position 7 with the assistance of the interrupter 82 and in this position further calling takes place. A relay L2 is repeatedly energized as follows over an interrupter 85 (10 second switch): earth, contact 83 u2, side switch contact 84 position 7, ringing relay L2, 10 second switch 85, battery, earth. Each time the ringing relay L2 operates, ringing current is transmitted as follows: earth, 85 source of ringing current 72b, contact 86 l2, winding II of the relay U2, side switch contact 87 position 7, over the wipers and the selected subscriber's line back over the side switch contact 80 position 7, earth. The calling party receives a ring back tone in positions 6 and 7 of the side switch, since a buzzer Su 1 is connected to the windings II of the relays A2 and B2 over the side switch contact 93 positions 6 and 7. During each ringing pause battery is connected up over the back contact 88 l2.

When the wanted subscriber answers during a ringing pause, the removal of his receiver establishes a direct current path, in 100 which the relay U2 can be energized by its winding II. The relay U2 opens the contact 83 u2 and prevents a further energization of the relay L2. It also closes its contact 89 u2, thereby energizing the relay F2 in 105 the following circuit: earth, contacts 90 a2, 89 u2, side switch contact 91 position 7, relay F2, resistance 48, battery, earth. The side switch reaches its position 8, in which the speaking leads are switched through over 110 the side switch contacts 92 and 93. The bridging relays A2 and B2, which now form the feeding bridge of the selected subscriber, operate over the subscriber's line. The relay A2 opens its contact 90 a2 and thereby prevents the side switch moving on from the 115 position 8 into the position 9.

When the wanted subscriber hangs up at 120 the end of the conversation, the relays A2 and B2 are de-energized so that the side switch moves on into the position 9, since the relay F2 is energized over: earth, contact 90 a2, side switch contact 92 position 8, relay F2, resistance 48, battery, earth.

When the calling party also hangs up, the circuit over the lead 1 (Fig. 3) leading to the second group selector is opened in known manner. The relay C1 thereupon releases and closes its contact 4 c1 and opens the contact 6 c1. The opening of this con- 125 130

tact interrupts the circuit over the relays P1 and C2 (Fig. 4). The relay P1 (Fig. 3) closes its contact 18 *p*1, thereby connecting up the release magnets M1 and M2 of the group selectors II.GWfa and II.GWfb: earth, contacts 13 *b*1, 16 *kfa* and 17 *kfb*, 18 *p*1, 4 *c*1, magnets M1 and M2, battery, earth. Both group selectors return to their normal position, in which the off-normal contacts 16 *kfa* and 17 *kfb* are opened and the off-normal contact 2 *kfa* is closed. The group selectors can now be taken into use for another connection.

At the final selector (Fig. 4) the interruption of the current flowing over the lead 24 causes the relay C2 to release and opens its holding circuit at the contact 41 *c*2. It thereupon causes the side switch to move from the position 9 into the position 10, since the relay F2 is energized over the contact 94 *c*2 and the side switch contact 95 position 9. In position 10 the relay F2 is energized over the contact 90 *a*2 and side switch contact 92. When the side switch reaches position 11 the winding II of the relay P2 is short circuited over the side switch contact 96, so that relay P2 releases. The circuit of the release magnet M3 is now closed: earth, contacts 97 *c*2, 67 *p*2, side switch contact 98 position 11, release magnet M3, battery, earth. The final selector therefore returns to its normal position, in which the off-normal contact 99 *k*3 is closed. The side switch is now moved on from the position 35 11 into the position 1, because the relay F2 is connected up over: earth, contacts 94 *c*2, 190 *p*2, side switch contact 101 position 11, off-normal contact 99 *k*3, relay F2, resistance 48, battery, earth. The final selector 40 has now been completely restored to normal.

If the line of the selector subscriber Tln 2 were engaged, the relay P2 would not have been energized in the position 4 of the side switch. Hence the side switch will remain 45 at present in the position 5, because the contact 70 *p*2 has not been closed. Over the side switch contact 102 position 5 an engaged tone is connected to the relays A2 and B2, so that the caller is notified that the wanted 50 line is engaged.

When the caller hangs up, the second group selector is released in the manner described, whereupon after the release of the relay C2 the release magnet M3 is connected up over the contact 97 *c*2 and the side contact 103 position 5, and returns the final selector to its normal position. After the release of the final selector, when the off-normal contact 99 *k*3 is closed, the relay F2 is energized 60 over the contact 94 *c*2, the side switch contact 104 position 5 and the off-normal contact 99 *k*3. The side switch is moved into the position 6 and thence into the position 7 by means of the interrupter 82 connected up 65 over the side switch contact 81. The relay

F2 is now energized over the contact 105 *c*2 and the side switch contact 91 position 7. In the positions 8 and 10 of the side switch the relay F2 is energized over the contact 90 *a*2 and the side switch contact 92. In position 9 the relay F2 is energized over the contact 94 *c*2 and the side switch contact 95 and in the position 11 it is energized over the contacts 94 *c*2, 100 *p*2, side switch contact 101 and off-normal contact 99 *k*3. 75

The case will now be considered, in which a connection is being set up to a private branch exchange. After the final selector has been set on the first contact of a P. B. X. it is necessary to select a free line going to the P. B. X. At the end of the train of impulses for setting the final selector on a particular contact, the side switch reaches the position 4 in the manner described. The first contact allotted to a P. B. X. subscriber at the final selector is a blank contact, to which no line is connected. The side switch momentarily remains in the position 4, because the slow releasing relay U2 was energized in the position 3. At the final selector a contact 54 *mk* is provided, which is closed as soon as the final selector is set on the blank contact of a P. B. X. Over this contact the relay A2 is energized: earth, contacts 51 *p*2, 52 *g*, multiple contact 54 *mk*, side switch contact 106 position 4, relay A2, resistance 107, battery, earth. The relay A2 connects up the winding I of the slow releasing relay U2: earth, contacts 108 *a*2, 109 *b*2, winding I of the relay U2 100 resistance 48, battery, earth: hence the relay U2 is maintained energized and the side switch remains for the present in the position 4. Furthermore the relay A2 also closes its contact 53 *a*2 and thereby connects 105 up the rotary magnet D3: earth, contacts 51 *p*2, 52 *g*, 53 *a*2, side switch contact 55 position 4, rotary magnet D3, battery, earth: the final selector is therefore moved on to the next line. At the same time, however, the magnet D3 at its contact 110 *d*3 short circuits the relay A2, which releases and by opening the contact 53 *a*2 interrupts the circuit of the rotary magnet D3. The rotary magnet D3 releases, removes the short 110 circuit round the winding I of the relay A2, so that this can again operate and can again close the circuit of the rotary magnet D3. This cycle is repeated until a free line to the selected P. B. X. has been found. Thereupon the relay P2 operates, and by opening the contact 51 *p*2 prevents the relay A2 and the rotary magnet D3 being again energized and it also effects the other operations described for a connection with a direct line 120 subscriber. As the contact 108 *a*2 is no longer closed, the relay U2 releases after a little while. The relay F2 is then energized over the contact 60 *a*2 and moves the side switch into the position 5. The further set- 125

130

ting up of the connection takes place in the same manner as for a call to a direct line subscriber.

If the final selector, while hunting for a free P. B. X. line, reaches the last line going to the P. B. X. it comes to rest on this contact even though this line be engaged. This is achieved because the contact 54 *mk* does not remain closed when the switch is set on 10 the last contact of a P. B. X. The circuit changes occurring when the last P. B. X. line is engaged are the same as those occurring when it is set on an engaged line of a direct line subscriber; hence this condition 15 need not be described.

A description will now be given of the circuit changes that occur when toll connections are set up. The case will first be considered in which direct line subscriber, 20 namely the subscriber *Tln* 2 is called by the toll exchange. In known manner the toll operator (FA) with the tip of the plug *Fst* (Fig. 2) tests the jacks *Kl* of the outgoing lines to see which are idle. On finding an 25 idle line, she inserts the plug into the corresponding jack thereby closing the following circuit: earth, battery, resistance 111, plug contact 112, jack bush 113, relay *CF* 1, earth. The relay *CF* 1 in known manner starts up 30 the preselector *I.FVW* associated with the jack, and the switch sets itself on a free succeeding numerical switch, for instance *I.GWf*. After the preselector has been positioned, a circuit is established over its 35 wiper 114, which energizes the relay *CF* 2, which then at contact 115 *c/2* connects earth to the test relay *P*3. After the group selector *I.GWf* has been raised to a particular level by a train of impulses transmitted 40 by the operator, the switch hunts for a free line in the selected contact group. When this has been found, the following circuit is established: earth, contact 115 *c/2*, relay *P*3, wiper 116, contact 117, lead 118 to Fig. 3, lead 1, contact 2 *kfa*, winding I of the relay *B*1, winding I of the relay *C*1, battery, earth. The relay *P*3 at the contacts 119 and 120 *p3* (Fig. 2) in known manner switches through 45 the speaking leads. The setting of the second group selectors *II.GWfa* and *II.GWfb* on to a particular contact group, the selection of a free final selector *LW* and the positioning of the latter on the contact of the wanted subscriber's line *Tln* 2 is effected in the manner described 50 for a local connection.

At the end of the train of impulses for setting the final selector on the contact of the wanted line, when the side switch reaches the 55 position 3, the relay *B*2 is energized in the following circuit because battery is automatically connected to one lead by the operator's impulse sender: earth, battery, impulse sender *Nu* in the cord circuit to the operator (Fig. 2), contacts 1121, 121 and 122, tip 123 of the plug *Fst*, jack spring 124, wiper 125, contacts 126, 119 *p3*, wiper 127, contact 128, lead 129 to Fig. 3, lead 9, contacts 27 *p1*, 29 *u1*, lead 31, wiper 33 of the group selector *II.GWfa*, contact 35, lead 37 70 to Fig. 4, contact 130 *g*, side switch contact 131 position 3, winding I of the relay *B*2. The relay *B*2 opens its contact 42 *b2* and thereby prevents the side switch being moved beyond the position 3. Furthermore 75 the relay *B*2 energizes relay *G* in the following circuit: earth, contacts 132 *b2*, 133 *f2*, side switch contact 134 position 3, relay *G*, battery, earth. The relay *G* 33 operates and at contact 130 *g* opens the circuit for energizing the relay *B*2, which however closed 80 the following circuit at the same time as the relay *G* was connected up: earth, winding I of relay *B*2, side switch contacts 131 and 135 position 3, contact 136 *b2*, lead 137, contact 138 (Fig. 3) and wiper 139 of the group selector *II.GWfb*, contacts 140 *p1*, 141 *f1*, winding of the relay *U*1, battery, earth. When the relay *G* at the final selector operated, it locked itself at its contact 142 *g* 90 in a holding circuit, which remains closed in the positions 3-5 of the side switch. At the second group selector the relay *U*1 operates and connects itself at contact 144 *u1* in the following holding circuit: earth, contacts 143 *c1*, 144 *u1*, winding II of the relay *U*1, battery, earth. The relay *U*1 disconnects the speaking leads 31 and 32 and the wipers 33 and 34 of the group selector 95 *II.GWfa* from the incoming line by opening 100 the contacts 29 *u1* and 30 *u1* and switches the incoming line over to the group selector *II.GWfb* at the contacts 145 *u1* and 146 *u1*. The test relay *P*1 which is connected to the test wiper 7 of *II.GWfa* is not 105 disconnected however and maintains the group selector in its operated position.

The connection to the wanted subscriber has now been so far set up that the toll operator can complete the connection at any 110 time. To do so, the toll operator throws the test key *PT* (Fig. 2) thereby opening the contacts 121 and 147, so that earth is connected at the contact 148 to one lead of the speaking line. Hence the following circuit is 115 established: earth, contact 148 of the test key *PT*, contact 149 of the key *TT*, contact 150 of the plug *Fst*, jack spring 151, wiper 152, contacts 153 and 120 *p3*, wiper 154, contact 155, lead 156 to Fig. 3, lead 11, contacts 28 *p1*, 146 *u1* and 157 *s1*, relay *F*1, battery, earth. The relay *F*1 operates and opens the holding circuit of the relay *B*2 at the final selector (Fig. 4), which circuit extends over the lead 137, the wiper 139 and the winding I 120 of the relay *U*1. The relay *B*2 releases and causes the side switch to move on into the position 4. In position 3 of the side switch the relay *U*2, having a slow releasing armature, was also energized, as explained in the de- 125 120

scription of the local connection: hence the side switch momentarily remains in the position 4. When the relay U2 has released, the side switch moves into the position 5, in which it remains until the release of the connection. All the switching devices for effecting the special circuit changes that only occur in toll connections are associated with the pair of group selectors II.GWfa and 10 II.GWfb. The testing to ascertain whether the selected subscriber's line is free or locally or trunk engaged is effected by test relays of these group selectors. It should now be mentioned that a slow acting relay V1 is connected 15 up when the relay U1 is energized: earth, contacts 158 u1, 159 x1, relay V1, battery, earth. The relay V1 at the contact 160 v1 prepares the circuit over the winding I of the relay X. When the relay F1 operates, owing to 20 the actuation of the test key PT, the circuit is closed for the slow acting relay X1: earth, contacts 160 v1, 161 f1, relay X1, winding I, battery, earth. At its contact 162 x1 the relay X1 connects the relay O1 to the wiper 25 164 of II.GWfb, this circuit having been prepared over the contact 163 v1 by the relay V1. The relay O1 is not operated for calls to direct line subscribers.

The relay X1 also connects the test relay 30 HR1 to the test wiper 139. The test circuit extends as follows: earth, relay HR1, contacts 165 o1, 166 x1, 167 hr1, 168 o1, 140 p1, wiper 139, contact 138, lead 137, contact 169 b2 (Fig. 4), test wiper 63 of the final selector, contact 64, relay 65, battery, earth. The relay HR1 tests whether the line is toll engaged. Only if it is toll engaged does the relay not operate, since in that case earth 35 is directly connected to the contact 64, but the relay operates if the subscriber's line is free or is locally engaged.

If the selected subscriber's line is toll engaged, the toll operator receives a buzzer signal, which is connected up as follows: 40 earth, induction coil 170 (Fig. 3), contacts 171 f1, 172 hr2, condenser 173, contacts 174 hr1, 1751, winding II of the relays E1 and F1, battery, earth. The buzzer signal is repeated to the toll operator by the relays E1 and F1 and she is notified that the wanted line is toll engaged.

If, however, the selected line is not engaged by a toll call and the relay HR1 therefore operates, a second test relay HR2 45 is connected to the test lead at the contact 176 hr1, this relay then determining whether the selected line is free or locally engaged. In the former case the relay HR2 operates and at its contact 177 hr2 short circuits the test relay HR1, which has locked itself at its contact 178 hr1. The relay HR2 also opens the contact 172 hr2 thus preventing the transmission of the toll engaged signal after the contact 174 hr1 has been closed: 50 hence the operator gets no signal if the sub-

scriber's line is free. If the selected line is locally engaged, the relay HR2 cannot operate. Hence the buzzer circuit for the locally engaged signal is closed as follows: earth, induction coil 179, relay R1, contacts 180 hr1, 1751, windings II of the relays E1 and F1, battery, earth. The relay R1 operates in this circuit and closes its contact 181 r1 thereby connecting the relay HR1 in parallel with the relay HR2. Thus two toll 55 connections are prevented from being simultaneously connected through to a line. Until the existing local connection has been released over the switch shown in the drawing, another toll operator can set up a toll 60 connection over other switches and from them can immediately release the local connection. Thereupon earth is directly connected to the contact 181 at another final selector LW' (Fig. 4) as is shown dotted. 65 Hence current is withdrawn from the relay HR1 and it releases and gives the toll operator the toll engaged signal.

If the subscriber's line is free, the relay 70 HR2 (Fig. 3) operates as described above and locks itself in a holding circuit over its winding II: earth, contacts 182 hr2, 140 p1, 183 hr2, winding II of the relay HR2, battery, earth. But over the contact 182 hr2 earth is also directly connected to the test 75 contact 64 of the selected line, hence the latter is completely blocked to other connections. This circuit extends as follows: earth, contacts 182 hr2, 140 p1, wiper 139, contact 138, lead 137, contact 169 b2 (Fig. 100 4) wiper 63, contact 64, relay 65, battery, earth.

To call the wanted line, the toll operator 105 presses the release key TT (Fig. 2) and thereby applies battery to one speaking lead, namely the lead to which the relay E1 at the second group selector is connected. The circuit extends as follows: earth, battery, contact 184 of the release key TT, plug tip 123, jack spring 124, wiper 125, contacts 126 110 and 119 p3, wiper 127, contact 128, lead 129 to Fig. 3, lead 9, contacts 27 p1, 145 u1, 185 s1, relay E1, earth. The energizing of the relay E1 causes the ringing relay L1 to be connected up: earth, contacts 186 f1, 187 hr2, 188 s1, 189 e1, 190 r1, ringing relay L1, battery, earth. The ringing relay L1 is energized at each operation of the release key TT, it opens its contacts 191 and 192 1, and at the contacts 193 1, and 194 1, connects 120 ringing current to the speaking leads. It remains to be mentioned that when the relay HR2 operates, it opens the contacts 195 hr2 and 196 hr2 and at the contacts 197 hr2 and 198 hr2 connects through the speaking 125 leads to the selected line. The ringing current takes the following path: earth, source of ringing current 199, contacts 193 1, 197 hr2, wiper 164, contact 200, lead 201, wiper 74 (Fig. 4) contact 75, lead 76, subscriber's 130

instrument Tln 2, lead 77, contact 78, wiper 79, contact 202 $u2$, lead 203, contact 204 (Fig. 3), wiper 205, contacts 198 $hr2$ and 194 1_1 , earth.

- 5 When the wanted subscriber answers, the feeding bridge relay $S1$ operates and by opening the contact 188 $s1$ prevents the relay L being again connected up. The relay $S1$ also, by opening the contacts 185 $s1$ and 157 $s1$, interrupts the circuit containing the relays $E1$ and $F1$ of the second group selector and the relay SR (Fig. 2) of the cord circuit of the toll operator. The relay SR is connected up when the dialling key ET is 10 returned to its normal position for the purpose of disconnecting the impulse sender after the toll operator has set up the connection. When the relay SR is energized, a clearing lamp SL is connected up over the contact 206 sr and the plug seat contact 207. The extinction of the clearing lamp notifies the operator that the wanted subscriber has 15 answered.

- When the wanted subscriber hangs up at 25 the end of the conversation, the relay $S1$ is de-energized and closes its contacts 157 $s1$ and 185 $s1$. Hence the relay SR (Fig. 2) in the toll operator's cord circuit is energized together with the relays $E1$ and $F1$ (Fig. 3). The relay SR connects up the clearing lamp SL , thereby notifying the operator that the conversation has finished.

- The release of the connection is effected by withdrawing the plug at the toll position, 35 whereby the relay CF is de-energized. This then opens the existing circuit over the wiper 114, causing the relay $CF2$ at the first toll group selector to release. The relay $CF2$ opens its contact 115 $cf2$ whereupon the 40 relays $P3$ and $C1$ (Fig. 3) are de-energized. The relay $P3$ (Fig. 2) in known manner releases the toll group selector $IGWf$. At the pair of group selectors $II.GWfa$ and $II.GWfb$ the relay $C1$ (Fig. 3) closes its 45 contact 4 $c1$ and thereby prepares the circuit for the release magnets $M1$ and $M2$. Furthermore, it opens its contact 6 $c1$, thereby opening the circuit over the test relay $P1$ of the second group selector pair and the 50 relay $C2$ at the final selector (Fig. 4). The relay $P1$ (Fig. 3) releases and at contact 18 $p1$ closes the circuit for the release magnets $M1$ and $M2$: earth, contacts 13 $b1$, 16 kfa , and 17 kfb , 18 $p1$, 4 $c1$, release magnets $M1$ and $M2$, battery, earth. Both group selectors are thereupon released.

- The side switch of the final selector (Fig. 4) stands in position 5 for toll connections as above explained. Upon the release of the 60 relay $C2$ the release magnet $M3$ is connected up over the side switch contact 103 position 5 and releases the final selector LW . When the final selector has reached its normal position, the off-normal contact 99 $k3$ is closed.

The relay $F2$, which controls the moving on 65 of the side switch by energizing the side switch magnet St , is now energized in the following circuit: earth, contact 94 $c2$, side switch contact 104 position 5, off-normal 70 contact 99 $k3$, relay $F2$, resistance 48, battery, earth. When the side switch reaches the position 6, the relay $F2$ is energized over 75 the side switch contact 81 and interrupter 82. In the further positions of the side switch, the relay $F2$ is energized as follows: 80 in position 7 over the contact 105 $c2$ and the side switch contact 91, in position 8 over the contact 90 $a2$ and side switch contact 92, in the position 9 over the contact 94 $c2$ and the side switch contact 95, in position 10 85 over the contact 90 $a2$ and in position 11 over the contacts 94 $c2$, 100 $p2$, side switch contact 101, off-normal contact 99 $k3$. The side switch is thus returned to its normal position (position 1).

If the selected subscriber's line is locally 90 engaged, this being indicated to the operator by a buzzer signal as above described, the operator can speak to the subscriber, because the speaking leads have been switched through over the condensers 235 and 236 (Fig. 3) and the contacts 237 $e1$ and 238 $e1$ and 239 $hr1$ and 240 $hr1$. After the subscribers have been notified of the operator's 95 intention to disconnect their local connection, the release key TT is pressed and thereby the relay $E1$ is energized in the same manner as when ringing current is connected up. The relay $E1$ opens the contacts 237 100 $e1$, 238 $e1$ and 241 $e1$ and closes the contacts 242 $e1$ and 243 $e1$. At the last mentioned contacts earth is connected to both speaking leads and thereby the release of the local connection is brought about in known manner. The relay $HR2$ operates when the local 105 connection has been released, because the contact 176 $hr1$ still remains closed. The relay $HR2$ short circuits the relay $HR1$ at the contact 177 $hr2$ and switches through the speaking leads at the contacts 197 $hr2$ and 198 $hr2$. If the wanted subscriber has hung 110 up, he is called in the same manner as when the line is free.

It will now be assumed that a toll call is 115 to be set up with a P. B. X. subscriber. As previously mentioned no line is connected to the first contact of a first P. B. X. subscriber, this blank contact being for preliminarily testing whether there are any free lines to the P. B. X. It is assumed that the contact 220 (Fig. 4) is the blank contact in front of the line group leading to a P. B. X. Earth is connected to this contact so long as there is a line still idle. When all the lines to the P. B. X. are engaged, the relays 65 I, 65 II, etc. associated with these lines, are energized either by outgoing or incoming calls. Over the contacts 221/65 I, 222/65, II, 120 125

etc. a relay V4 is connected up, which, by opening the contact 223 *v4*, disconnects earth from the blank contact 220.

The contact 54 *mk* is closed at the same time when the final selector is set on the blank contact 220. When the relay B2 releases at the end of the train of impulses for setting the final selector on the blank contact of the wanted P. B. X. the side switch 10 is brought into the position 3 in the manner described. In this position the relay B2 is again energized over the lead 37, the contact 130 *g* and the side switch contact 131. The relay B2 keeps the side switch in the position 3, because the contact 42 *b2* is opened. Furthermore in position 3 of the side switch the relay U2 is energized over the side switch contact 59. The relay U1 at the second group selector is now again energized 20 over the lead 137, the contact 136 *b2* and the winding I of the relay B2. The relay U1 then connects up the relay V1.

When the toll operator presses the test key PT (Fig. 3) the energizing of the relay F1 (Fig. 3) opens the circuit over the relays U1 and B2. The relay B2 releases and the side switch reaches the position 4. Here it remains because the relay U2, which was energized in the position 3, is provided with a slow releasing armature. The energizing of the relay F1 causes the relay X1 to be energized by its winding I over the contact 161 *f1* and furthermore the contact 228 *f1* is also closed. Testing now takes place to ascertain whether any lines to the P. B. X. are free. If there are any free, the relay O1 is energized over its winding I as follows: earth, battery, winding I of the relay O1, contacts 163 *v2*, 162 *x1*, 195 *hr2*, 40 wiper 164, contact 200, lead 201, wiper 74 (Fig. 4), blank contact 220, contact 223 *v4*, earth. The relay O1 operates and opens the short circuit round its holding winding II at the contact 226 *o1*. At the same time, 45 however, the following circuit is closed: earth, contacts 228 *f1*, 225 *v1*, windings II and III of the relay X1, winding II of the relay O1, contact 229 *hr1*, 196 *hr2*, wiper 204, lead 203, contacts 230 *u2* (Fig. 4), 328 50 *g*, 54 *mk*, side switch contact 106 position 4, relay A2, resistance 107, battery, earth. The relay A2 operates and the relays X1 and O1 are maintained energized. The relay A2 closes its contact 53 *a2* and thereby connects its own winding in parallel with the rotary magnet D3. The latter cannot operate, at present however, owing to the high resistance winding II of the relay X1. The relay A2, by closing the contact 108 *a2*, maintains the relay U2 energized, so that the side switch remains in the position 4 since contact 60 *u2* remains open. As the relay O1 is energized, the relay HR2 is connected to the test wiper 139. Testing for a free line 65 now takes place.

When the slow relay V1 at the second group selector has released after its circuit was opened at contact 159 *x1* upon the energization of the relay X1, the high resistance winding II of the relay X1 is short circuited at the contact 231 *v1*. Thereupon the rotary magnet D3 (Fig. 4) can be energized by earth connected up over the contact 327 *x1* (Fig. 3). The rotary magnet D3 moves the final selector on to the next contact, and at the contact 110 *d3* short circuits the relay A2, which opens the contact 53 *a2*. The rotary magnet D3 releases. This cycle is now repeated until a free line is found whereupon the relay HR2 operates, and locks itself up over its winding II and the contacts 182 *hr2*, 140 *p1*, and 184 *hr2* and at the same time marks the selected line toll engaged by applying earth over the contact 182 *hr2*.

It may happen that while hunting for a free P. B. X. line is taking place, the last free line is taken into use by another party. When the final selector reaches the last line, the contact 54 *mk* is opened, thereby releasing the relays O1 and X1. The relay X1 is, however, rendered slow releasing owing to the winding II being short circuited, hence the contact 166 *x1* remains closed a little while after the contact 165 *o1* has been closed. If the last line is locally engaged therefore, the relay HR1 operates and at its contact 180 *hr1* connects up a buzzer, which notifies the toll operator that the line is locally engaged. In order that the toll operator can communicate with the speaking subscribers, the speaking leads are switched through by the relay HR1 in the manner described for setting up a toll call to a direct line subscriber. Also the local connection is released and the toll connection finally set up in the same manner. If, however, the line is toll engaged, the relay HR1 cannot operate and the operator receives the toll engaged signal over the contact 174 *hr1*.

If there are no free lines when the final selector is set on the blank contact, earth is disconnected from the contact 220 and the relay O1 therefore cannot operate. Hence the relay HR1 remains connected to the test wiper 139 over the contacts 165 *o1*, 166 *x1*, 167 *hr1*, 168 *o1* and 140 *p1*. It operates as soon as the final selector LW reaches a locally engaged line, stops the final selector by opening the circuit over the relays X1 and A2 and gives the locally engaged signal to the toll operator. The release of the local connection and the calling and the release of the switches at the end of the conversation take place in the manner described for a toll connection to a direct line subscriber.

In the examples shown it is assumed that there are two group selectors II.GWfa and II.GWfb, connected in parallel each of

which has separate driving and release magnets. Instead of having two switches, however, it is obvious that one switch with two sets of wipers can be used, both the sets of 5 wipers being mounted on the same shaft and arranged to wipe over different contact banks.

What I claim is:—

1. In a telephone system, means including 10 a selector and a rotary connector for extending a connection to the first idle line in a group, means in said connector including an impulsing relay and a stepping magnet controlled by said impulsing relay for giving 15 its wipers a hunting movement, and means in the selector for controlling said impulsing relay.

2. In a telephone system, means including 20 a selector, a trunk line and a rotary connector terminating said trunk line for extending a connection to the first idle line in a group, means in said connector for giving 25 its wipers a hunting movement, and means in the selector controlled over a non- talking conductor of said trunk line for stopping such hunting movement when an 30 idle line is found.

3. In a telephone system, means including 35 a selector and a connector for extending a connection from a calling line to a called line, means in the selector for testing the connected called line to determine if the same is busy or idle, and means controlled over the calling line after the connection 40 is established for starting the testing operation at will.

4. In telephone system, a combination toll 45 and local connector for extending a connection to a called line, toll and local selectors for extending toll and local calls to said connectors, respectively, means in said combination connector for testing a called line effective in case the connector has been seized by a local selector, and testing means in 50 each toll selector so that in case the connector is seized by a toll selector the called line is tested from such toll selector.

5. In a telephone system, a group of lines, 55 any number of which may be idle, locally busy, or toll busy, a first automatic switch having access to said lines, a second automatic switch, means for operating said second switch to connect with said first switch, means for operating said first switch 60 to successively connect with the first idle line providing one exists, or the first locally busy line providing none of the lines is idle and one of the lines is locally busy, and means in said second switch for controlling said second means.

6. In a telephone system, a group of lines, 65 a first automatic switch having access to said lines, a second automatic switch, means for operating said second switch to connect with said first switch, a first and a second

trunk terminating in said second switch, means controlled over either of said trunks for operating said first switch into selective relation with said lines, means for then operating said first switch to successively connect with said lines, testing means in said first switch rendered effective when the operation of said first switch is controlled over one of said trunks, and testing means in said second switch rendered effective when the 70 operation of said first switch is controlled over the other of said trunks.

7. In a telephone system, a group of lines any of which may be idle, engaged in a toll connection, or engaged in a local connection, 75 a first automatic switch having access to said lines, a second automatic switch, means for operating said second switch to connect with said first switch, means for operating said first switch into selective relation with said 80 lines, means in said first switch for giving its wipers a hunting movement, testing means in said second switch for controlling the hunting movement of said first switch sensitive to idle lines, second testing means in 85 said second switch for controlling the hunting movement of said first switch sensitive to locally busy lines or idle lines, means for placing the hunting movement under the control of said first testing means in case 90 there is an idle line available, and for placing said hunting movement under the control of the other testing means in case all of 95 said lines are busy.

8. In a telephone system, a group of lines 100 any of which may be idle, engaged in a toll connection, or engaged in a local connection, a first automatic switch having access to said lines, a second automatic switch, means for operating said second switch to connect with said first switch, means for operating said first switch into selective relation with said 105 lines, testing means in said second switch, and means controlled by said testing means for causing said first switch to connect with the first idle line in said group providing there is one idle, or connect with the first 110 locally busy line in said group providing all of said lines are either toll or locally engaged.

9. In a telephone system, means including 115 a selector and a rotary connector for extending connections to a line in a group, means in said connector for giving its wipers a hunting movement, testing means in said selector, and means under the control of said testing means for stopping such hunting movement when an idle line is found providing there is an idle line in the group, and means for stopping such hunting movement 120 when a locally engaged line is found providing all said lines are either toll or locally engaged.

10. In a telephone trunking system, combination toll and local connectors, combina- 130

- tion toll and local selectors having access to said connectors, discriminating means in each combination switch for causing it to operate differently in toll and in local connections and local selectors also having access to said connectors.
11. In a telephone trunking system, toll first selectors and local first selectors, combination toll and local second selectors accessible to said toll first selectors and to said local first selectors, local second selectors accessible only to said local first selectors, and combination toll and local connectors accessible to said toll and local second selectors and to said local second selectors.
12. In a telephone system, a rotary connector having a controlled directive movement and an automatic hunting movement for extending a connection from a calling station to an idle line of a group, an impulsing relay in said connector, a stepping magnet in said connector under the control of said relay, means for operating said relay responsive to and in accordance with the calling device at the calling station for controlling the directive movement of said connector and means for automatically operating said relay to control said hunting movement.
13. In a telephone system, a subscriber's line which may be either idle, engaged in a local connection, or engaged in a toll connection, means including a selector and a connector for extending a connection to said line, and means in said selector for testing said line to determine whether the same is idle, is busy in a local connection, or is busy in a toll connection.
14. In a telephone system, a group of lines any one or more of which may be idle, locally engaged, or toll engaged, an automatic switch, and means for operating said switch to select an idle line of said group providing one of said lines is idle and for operating said switch to select a locally engaged line providing all the lines of said group are either toll engaged or locally engaged.
15. In a telephone system, a group of lines any one or more of which may be idle, locally engaged, or toll engaged, an automatic switch, means for operating said switch into selective relation with said lines, and means automatically operative thereafter for causing said switch to select the first idle line of said group providing one or more is idle, or the first locally busy line of said group providing none of the lines is idle and one or more is locally busy.
16. In a telephone system, a group of lines any one or more of which may be idle, locally engaged, or toll engaged, an automatic switch, means for operating said switch into selective relation with said lines, and means for stopping said switch when an idle line is reached or when a locally engaged line is reached providing none of the lines of said group is idle.
17. In a telephone system, a group of lines any one or more of which may be idle, locally engaged, or toll engaged, an automatic switch, means for operating said switch into selective relation with the lines of said group successively, and means for stopping said operation when an idle line is reached or when a locally engaged line is reached providing none of the lines of said group is idle.
18. In a telephone system, a group of lines any one or more of which may be idle, locally engaged, or toll engaged, an automatic switch, a trunk comprising talking conductors and a non-talking cord terminating said switch, means controlled over one talking conductor for operating said switch into selective relation with the lines of said group successively, and means controlled over said non-talking conductor for stopping said operation when an idle line is reached, or when a locally engaged line is reached providing all the lines are toll engaged.
19. In a telephone system, a group of lines any one or more of which may be idle, locally engaged, or toll engaged, an automatic switch, means for operating said switch into selective relation with said lines successively, a first test relay responsive when an idle line is reached for stopping said operation, a second test relay responsive when a locally engaged line is reached for stopping said operation, and means for determining which of said relays is to govern the stopping of said operation.
20. In a telephone system, a group of lines any one or more of which may be idle, locally engaged, or toll engaged, an automatic switch having line wipers and a test wiper, means for operating said wipers into selective relation with said lines successively, a first test relay responsive when controlled over said test wiper when an idle is reached for stopping said operation, a second test relay responsive when controlled over said test wiper when a locally engaged line is reached for stopping said operation, and means controlled over one of said line wipers for determining which of said relays is to be controlled over said test wiper.

In testimony whereof I affix my signature.
ALFRED SCHEUNERT.
